UNITED STATES PATENT OFFICE.

HENRY W. COTTRELL, OF RICHMOND, VIRGINIA, ASSIGNOR OF ONE-HALF TO HENRY W. ROUNTREE, OF RICHMOND, VIRGINIA.

TRUNK-LOCK.

Specification of Letters Patent.

No. 928,905.

Application filed May 21, 1909. Serial No. 497,460.

Patented July 20, 1909.

To all whom it may concern:

Be it known that I, HENRY W. COTTRELL, a citizen of the United States of America, residing at Richmond, Virginia, United States of America, have invented in certain new and useful Improvements in Trunk- Locks; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 My invention relates to locking mechanism or latches for the doors or followers of trunks, especially for that class of trunks known as wardrobe trunks.

20 a simple, efficient and compact mechanism including a plurality of latches and means to simultaneously actuate the bolts of said latches against the action of their projecting springs by means of a single rod or a rod 25 composed of a plurality of connected sections having cam members for engaging and actuating the bolts, together with details of construction hereinafter more particularly described in the specification and pointed out 30 in the claims.

Referring to the drawings, in which like parts are similarly designated, Figure 1 is an elevation of a portion of a trunk door or follower with parts broken away and parts 35 in section to clearly show the assembled mechanism. Fig. 2 is an enlarged detail view partly in section of one of the bolts and its actuating cam. Fig. 3 is a longitudinal section on the line 3—3 of Fig. 2 and Fig. 4 is a transverse section on the line 4—4 of Fig. 3. Fig. 5 is a longitudinal section of a modification. Fig. 6 is a section on the line 6—6 of Fig. 5 and Fig. 7 is a perspective view of a portion of the actuating rod showing the manner in which the cam is formed.

45 A portion of a trunk door or follower is indicated at 1 and secured thereto are a number of latches 2, 3 and 4, each including a latch case in which is operatively mounted a 50 spring urged bolt 5 projected beyond the edge of the door or follower. To the inner end of each bolt is secured or formed thereon

an abutment, herein shown as an anti-friction roller 6. Mounted in slidable relation to said abutments or anti-friction rollers are 55 cams 7 on and preferably integral with a sheet metal rod or strip 8, which rod is preferably, but not necessarily, made in sections 8 connected together end to end by split rivets 9 or otherwise, so that these sections can 60 be readily separated when it is necessary to remove a latch for repairs or for other purposes. The cam 7 is formed or for other purposes. The cam 7 is formed by making a metal at an angle to the edge of the strip and 65 at right angles to the face of the strip and then trimming off the turned-up portion so as to be of substantially uniform height. The transverse cut forms a shoulder 8^b which 7 in its normal position rests on the antifriction rollers and acts as a limit or stop for the rod. The rod 8 preferably passes through lateral openings 10 in the latch cases and is guided between the edges of said opening and the friction roller 6, but in addition thereto I provide guide strips 11 secured to the door or follower in any suitable manner to insure rectilinear movement of the rod under all conditions. The rod consequently moves in a right line and is provided with a handle comprising a plate 12 covering a slot, said plate having an operating ring secured thereto by means of rivets in the rod and more particularly in the manner shown and described in my co-pending application filed March 23, 1909, Ser. No. 485,211.

Riveted to the rod is a loop 13 and secured to the door or follower in immity to said loop is a lock 14 whose 15 is capable of entering the loop which the actuating rod 8 may be locked a unauthorized operation.

Ordinarily the springs on the late will be sufficient the springs on the late weight of the rod in conjunction w normal position, but in return said ro positive operation of the rod under 16 to which is connected at one end 17 and whose other end is secured to or follower at 18 by a screw or oth Surrounding the locking mech

a number of cleats 19 forming a recess with-
in which the locking mechanism is concealed
and the recess and strips are covered by a
suitable covering board 20 or its equivalent,
thereby effectively concealing the locking
mechanism within the door or follower.

I make use, in connection with the afore-
said described mechanism, of two forms of
spring latches each comprising a casing and
10 a spring actuating bolt operatively secured
therein and each bolt provided with an abut-
ment preferably an anti-friction roller at
its inner end. In both forms of latch shown
15 in Figs. 2 to 6, the casing is composed of
sheet metal and consists of two parts one a
flat plate 21 and the other a channel shaped
plate 22, the depth of the channel being
somewhat greater than the thickness of the
20 door or follower 1 as clearly shown in Figs.
3 to 6. The bolt is held to the flat base
plate 21 by means of a sheet metal strap 23
against which abuts a plate 24 loose on the
shank 25 of the bolt and this plate 24 is its actuating
25 spring 26 surrounding the shank 25. The
channel shaped portion of the case is pro-
vided with lateral openings as indicated at
10 in order that the actuating rod may be
free to pass through the same. In these re-
spects the two forms of latches are identical
but the form of latch shown in Figs. 2 to
4 comprises the following features. The
tail of the bolt shank that passes through
the strap 23 is flattened at 27, Fig. 3, has
riveted thereto a member 28, the two to-
gether forming a fork, and between the ends
of the flattened portion 27 and of the mem-
ber 28 is included the abutment or anti-
friction roller 6. The rod or rod section
passes through the slot formed between the
28 flattened portion of shank 27 and the mem-
ber 28 with the up-turned inclined cam 7
against the roller 6, the back edge of
the rod lying against the outwardly turned
ges 29, Fig. 2, at the left hand side of
opening 10. The sides of the flattened
ion of the bolt shank and of the member
re guided between anti-friction rollers
ounted on rivets 31 passing through
the upper and lower case members 21
2. These rollers are also in proximity
edge of the opening 10 so that the rod
ive bearing on them as it is recipro-
In the second form of bolt, shown in
and 6, the shank 25 of the bolt passes
a U-shaped metal strip 31 and is up-
riveted thereto thereby forming a
nd and between the ends of this
mounted the abutment or anti-fric-
6. The flanges of the channel
ortion of the case lie against the
21 and the retaining strap 23 for
placed between them so that when
r otherwise securing the latch to
r follower the rivets 32, Fig. 2,

will pass through all three thicknesses of
metal while the rivets 33 pass through only
two thicknesses of metal.

I claim:—

1. The combination with a trunk door or
follower and a plurality of latches secured
thereto and having spring urged bolts pro-
jecting beyond the edge thereof; of an abut-
ment on each bolt shank and a longitudi-
nally reciprocable rod having cams thereon,
said rod being mounted in operative rela-
tion to said abutments with the cams con-
tacting therewith.

2. The combination with a trunk door or
follower and a plurality of latches secured
thereto having spring urged bolts pro-
jecting beyond the edge thereof; of abut-
ments on the bolt shanks and a longitudi-
nally reciprocable, sectional rod and a cam
on each section thereof, said rod being
mounted in operative relation to said abut-
ments with the cams contacting therewith.

3. The combination with a trunk door or
follower and a plurality of latches secured
thereto and having spring urged bolts pro-
jecting beyond the edge thereof; of an anti-
friction roller on each bolt shank and a lon-
gitudinally reciprocable spring urged rod
having cams thereon, said rod being mount-
ed in operative relation to said rollers and
the cams contacting therewith.

4. In a latching mechanism for trunk
doors or followers, a latch actuating rod
comprising a sheet metal strip having a
transverse cut extending partly across the
strip and a portion of metal turned up at an
angle to the edge of the strip and cut off
substantially parallel with the strip to form
a cam surface substantially perpendicular
to the face of the strip and inclined to its
longitudinal direction.

5. In a latching mechanism for trunk
doors or followers, a latch actuating rod
comprising a plurality of sheet metal sec-
tions each having a transverse cut extending
partly across the section and a portion of
metal turned up at an angle to the edge of
the section and cut off substantially parallel
with the rod to form a cam surface substan-
tially perpendicular to the face of the strip
and inclined to its longitudinal direction.

6. The combination with a cam rod, of a
latch comprising a flat plate a spring urged
bolt secured thereto, an abutment carried by
the shank of said bolt, said abutment coöp-
erating with the cam on the rod, a channel
shaped sheet metal cover plate having lateral
openings one edge of said openings form-
ing a guide for the back edge of the cam rod.

7. The combination with a cam rod, of a
latch comprising a flat plate, a spring urged
bolt secured thereto, an anti-friction roller
carried by the shank of said bolt, said anti-
friction roller coöperating with the cam on
the rod, a channel shaped sheet metal cover-

ing plate having lateral openings, one edge of said openings forming a guide for the back edge of the cam rod, and anti-friction rollers mounted in the casing on each side of the bolt shank and in proximity to the edges of said openings to contact with the back of said rod.

8. The combination with a door or follower, and a plurality of spring-urged latches, each having a yoke connected to its shank; of an actuating rod passing through the yokes of the latches and cams on the rod to engage the yokes, and means connected to the rod and passing a slot in the door to actuate the rod, whereby said means and rod may be given simultaneous rectilinear movement to actuate the latter.

9. The combination with a plurality of spring-urged latches each having an abutment thereon; of a sectional actuating rod, the sections of which are detachably connected end for end, a cam formed on each section and a shoulder adjacent each cam

capable of striking the abutment on the latch.

10. The combination with a plurality of spring-urged latches each having an abutment thereon; of a sectional actuating rod, the sections of which are detachably connected end for end, and a cam formed on each section capable of striking the abutment on the latch.

11. The combination with a plurality of spring-urged latches each having an abutment thereon; of a sheet metal actuating rod comprising detachable sections, a cam on each section to engage the latch abutments, and a spring to urge the rod downward.

In testimony that I claim the foregoing as my invention, I have signed my name in presence of two subscribing witnesses.

HENRY W. COTTRELL.
